Attn:

UNITED STATES PATENT OFFICE.

CHARLES HENRY SNIVELY, OF SUNBURY, PENNSYLVANIA.

DISPLAY-RACK.

SPECIFICATION forming part of Letters Patent No. 674,069, dated May 14, 1901.

Application filed July 25, 1900. Serial No. 24,750. (No model.)

To all whom it may concern:

Be it known that I, CHARLES HENRY SNIVELY, of Sunbury, in the county of Northumberland and State of Pennsylvania, have invented certain new and useful Improvements 5 in Display-Racks, whereof the following is a specification, reference being had to the accompanying drawings.

My invention relates to devices particularly adapted for the display of such merchandise as carpets, oil-cloths, and similar fabrics.

My invention comprises a clamp or series 15 of clamps each arranged to secure a group of sample sheets of fabric, a panel upon which the clamped sheets may be selectively displayed, a pair of opposed standards at one extremity of said panel respectively provided with slots, and means to removably secure 20 said clamp or clamps in said slots.

I have shown a convenient embodiment of my invention in the accompanying drawings, wherein—

Figure 1 is a rear view of the display-rack. 25 Fig. 2 is a sectional view of said rack, taken on the line 2 2 in Fig. 1; and Fig. 3 is a perspective view of the top of one of the standards.

In said figures, A is the base of the rack, 30 preferably provided with feet a. The opposed standards B are connected by the base A at their lower extremities and by the cross-bar C intermediate of their length, and the inclined panel D is supported by the said base and cross-bar, as shown in Fig. 2. The upper extremities b of said standards B are bifurcated by respective slots b', which are opposed in alignment and adapted to receive the sheet-clamps E E' E². Said clamps are 35 in removable relation with the standards B, but are conveniently retained therein by means of the swinging bails F, which, as indicated in Fig. 3, are each pivoted in one fork of the respective standard and arranged to 40 embrace the other fork thereof. Each of said clamps E E' E² comprises a pair of opposed bars (respectively marked e e' e²) and is provided at its opposed extremities with bolts G and nuts g, by which the respective pairs 45 of opposed bars are caused to clamp a sheet or series of sheets of fabric H H' H², which

are interposed between the respective bars, as shown in Fig. 2.

By the arrangement above described any desired number of sample sheets of fabric 55 may be arranged for display upon a single rack, selected groups of the sheets being secured in clamps, such as E E' E², which may be placed as desired in the slots b' of the standards B. When so placed, any particular sheet of fabric I may be displayed upon the panel D by turning the superimposed sheets over the top of the rack, as indicated in Fig. 2. Although the embodiment of my invention which I have chosen for illustration 60 contains but three of the clamps, (respectively designated E E' E²), it is to be understood that the slots b' in the opposed standards B may be so proportioned as to contain any desired number of such clamps, and 65 although I have shown five sheets of the fabric in each of said clamps it is to be understood that each clamp may contain any desired number of sample sheets.

I do not desire to limit myself to the precise details of construction which I have shown, as it is obvious that various modifications may be made therein without departing from the essential features of my invention.

I claim—

1. In a display-rack, the combination with a clamp arranged to secure a sample sheet of fabric, of a panel upon which the clamped sheet may be displayed, a pair of opposed standards at one extremity of said panel respectively provided with slots, and means to removably secure said clamp in said slots, substantially as set forth.

2. In a display-rack, the combination with a clamp arranged to secure a sample sheet of fabric, of an inclined panel upon which the clamped sheet may be displayed, a pair of opposed standards at one extremity of said panel respectively provided with slots, and means to removably secure said clamp in said standards, substantially as set forth.

3. In a display-rack, the combination with a clamp arranged to secure a sample sheet of fabric, of a pair of opposed standards respectively provided with slots, and swinging bails upon the respective standards arranged

to removably secure said clamp in said slots, substantially as set forth.

4. In a display-rack, the combination with a base, of a pair of opposed standards in fixed relation with said base, and respectively provided with slots, a cross-bar connecting said standards intermediate of their length, a panel supported in inclined posi-

tion upon said base and said cross-bar, and a sheet-clamping device mounted in said slots in removable relation with said standards, substantially as set forth.

CHARLES HENRY SNIVELY.
